INSOLE MACHINE

Filed July 5, 1919

Patented Sept. 9, 1924.

UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

INSOLE MACHINE.

Application filed July 5, 1919. Serial No. 308,856.

To all whom it may concern:

Be it known that I, JOHN B. HADAWAY, a citizen of the United States, residing at Swampscott, in the county of Essex and State of Massachusetts, have invented certain new and useful Improvements in Insole Machines; and I do hereby declare the following to be a full, clear, and exact description of the invention, such as will enable others skilled in the art to which it appertains to make and use the same.

The present invention relates to machines for operating upon insoles and more particularly to machines of this character employed in connection with the manufacture of reinforced insoles.

It is an object of the present invention to provide certain improvements in the mechanism for trimming the reinforcing fabric during the application of the fabric to an insole or as a separate operation.

In the present invention the trimming mechanism is employed in connection with the reinforcing of "Gem" insoles in which the reinforcing fabric extends about opposite sides of the insole lip and partly across the feather, being trimmed on a line lying inside of the edge of the insole. Accordingly a feature of the invention relates to a trimming knife arranged to sever the reinforcing fabric during the feeding of the insole, combined with a presser foot which rests upon the feather of the insole after the reinforcing fabric has been applied thereto and properly gages the cut of the knife to cause the latter to completely sever the fabric without making any substantial incision in the body of the insole. This knife is gaged laterally of the sole by the outside lip former and accordingly trims the fabric at a uniform distance from the base of the lip throughout the length of the reinforce.

Still further features of the invention consist in certain novel features of construction, combinations and arrangements of parts hereinafter described and claimed, the advantages of which will be obvious to those skilled in the art from the following description.

In the accompanying drawing illustrating the preferred form of the invention, Figure 1 represents a partial front elevation of an insole reinforcing machine showing the im-

proved trimming mechanism embodied 55 therein; Fig. 2 is a right hand side elevation of the trimming knife and cooperating parts; Fig. 3 is a left hand side elevation of the mechanism shown in Fig. 2; and Fig. 4 is a plan view of the knife block and 60 trimming knife carried therein.

The illustrated embodiment of the invention is conveniently applied to the machine disclosed in the patent to Hadaway No. 614,860, November 29, 1898. This machine 65 comprises a rotary table 10 upon which the insole is supported and a feeding foot 12 supported upon a vertical slide 13 and having the auxiliary foot 14 adapted to engage with the top of the lip in the usual 70 manner. Cooperating with the feeding foot 12 is a stationary outside former 15 shown in Fig. 3 and broken away in Fig. 1. The usual inside former which is supported upon one arm of a bell crank indicated at 17 is 75 caused to yieldingly engage with the inner side of the lip through the provision of the spring 18, the stem of the former being shown broken away at 19, Fig. 1. The forming members cooperate in the usual manner to feed the work and shape the reinforcing fabric about the lip of the insole, all as fully described in the Hadaway patent 80 hereinbefore referred to.

It is highly desirable in this type of machine 85 that the reinforcing fabric shall be severed cleanly along a line conforming to the general contour of the insole and in such a manner that the edge of the fabric shall not show after the insole is incorporated in a boot or shoe. To this end the fabric is severed, after it has been laid upon the feather by the forming tools, along a line which is spaced a uniform distance from the base of the lip and slightly within 90 the edge of the insole. The trimming of the fabric is accomplished by a stationary drag knife which engages and cuts the fabric during the feeding of the insole, a presser foot which rests upon the feather 95 of the insole controlling the depth of cut.

For this purpose, a drag knife 20 is provided, being received in a knife block 21 pivoted upon a fixed bracket 22. The knife block 21 is provided with an L-shaped lower 100 end 25 having one portion extending substantially in the line of feed at the side of the knife and a second portion at right

angles thereto extending across the line of feed which rests upon the face of the insole and acts as a presser foot to gage the depth of cut made by the knife. This lower portion of the knife block is provided with a curved deflecting surface 26 which serves to direct the severed portion of the fabric out of the machine. The knife block is pivoted upon a fixed stud 28 clamped at one end in a split hub 29 formed upon the bracket 22, a clamping screw 30 serving to draw the two parts of the hub together and bind the stud in position. The hub portion of the knife block 21 is provided with an upwardly extending tail 31 which carries an adjusting screw 32 adapted to limit the downward movement of the free end of the knife block through contact with the opposing face of the bracket 22, as shown clearly in Figs. 1 and 4. The knife block and knife carried thereby are normally pressed into engagement with the work by a plunger 35 slidably received within the bracket 22 and engaging with the upper face of the knife block, a spring 36 serving to apply the requisite pressure to the plunger. It will be noted that this bracket 22 conveniently carries the stationary outside former 15 which is adjustably fastened thereto through a screw and slot connection, indicated at 37. The stationary bracket 22 is connected to a depending portion 38 of the machine frame through tongue and groove connections 40 and a clamping screw 41, as shown in Figs. 2 and 3, thus affording provision for a transverse adjustment of the knife and stationary former across the line of feed. In order to adjust the depth of cut made by the knife for varying thicknesses of reinforcing fabric or other reasons, the knife is provided with rack teeth 42 on the under edge which are engaged by a single toothed adjusting pinion 43, the side of which has a slot, as shown in Fig. 1, into which a screw driver or other tool may be inserted for rotating the pinion. The knife is clamped in adjusted position in the knife block by the head of a clamping screw 44. With this construction it will be noted that the trimming knife cuts to a measured depth predetermined by the relation of the knife and presser foot both of which are yieldingly pressed against the work with sufficient pressure to properly maintain the presser foot in contact with the surface of the feather. In order to prevent injury to the knife if the machine is operated without an insole located upon the table, the latter is provided with a peripheral groove 46 positioned beneath the knife and into which the knife may enter when the table rises under the influence of its spring. The screw 32 is so adjusted as to permit the knife to be yieldingly held against the sole while trimming the reinforce and,

therefore, the presser foot may extend to a position slightly below the lower end of the stationary former 15.

It will be recognized by those skilled in the art that the canvas trimming feature of the machine herein described is not limited in its use to a combination with bead forming instrumentalities, but will perform its function with equal facility if the inside canvas forming tool is disconnected or removed. In this event the machine may be employed as a canvas trimming machine for operating on previously reinforced soles.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A machine for operating on reinforced insoles having, in combination, means for supporting and feeding the insole, a knife having a cutting blade opposite the feather for severing the reinforcing material along a line on the feather, a presser foot independent of the feeding means and bearing on the feather to predetermine the depth of the cut, and means through the actuation of which the relation of said knife and foot may be adjusted for varying the depth of the cut.

2. A machine for operating on reinforced insoles having, in combination, a frame, means in the frame for supporting and feeding the insole, a knife having a cutting blade opposite the feather for severing the reinforcing material along a line on the feather, a knife block adjustably secured to the frame and in which said knife is carried, a presser foot mounted on said block independently of the feeding means, and means through the actuation of which the relation of said knife and presser foot may be adjusted, and means by which said parts may be clamped in adjusted relation.

3. A machine for operating on reinforced insoles having, in combination, means for supporting and feeding the insole, a knife having a cutting blade opposite the feather for severing the reinforcing material along a line on the feather, and a knife block and presser foot to which the knife is adjustably clamped and constructed and arranged to predetermine the depth of cut, the lower surface of said presser foot bearing on the feather over a substantial area both beside and behind said knife in the direction of feed.

4. A machine for operating on reinforced insoles having, in combination, means for supporting and feeding the insole, a support

- having a flat work-engaging surface, a knife opposed to said support, for severing the reinforcing material along a line on the feather, having its cutting blade normal to the surface of said support, a presser foot also having a flat, work-engaging surface parallel to the surface of said support and bearing on the feather to predetermine the depth of cut, means whereby the projection of said blade below said foot may be adjusted so that no substantial incision will be made in the feather and means acting continually to force the work support toward the knife, said flat surface of the support being provided with a groove to receive said blade when no work is in the machine.
5. A machine for operating on reinforced insoles having, in combination, a work support, a drag knife opposed to said support for severing the reinforcing material along a line on the feather, means for feeding the sole past said knife, means for main-
- taining a predetermined depth of cut irrespective of variations in sole thickness including a presser foot independent of said feeding means and having an L-shaped bearing surface engaging said feather and means through the actuation of which the depth of cut may be varied.
6. In a sole trimming machine, a knife block, a knife carried thereby having a toothed shank, and a single-toothed pinion rotatably mounted in the block with its tooth meshing with the teeth on the shank of said knife, whereby a rotation of the pinion will adjust the knife on the block.
7. In a reinforced-insole trimming machine, a fabric trimming knife, a knife block therefor, and a presser foot on said block to predetermine the depth of cut, said foot having a curved deflecting surface on its sole engaging end to direct the trimmed margin out of the machine.

JOHN B. HADAWAY.
